United States Patent Office

Des. 217,152
Patented Apr. 14, 1970

217,152

TAPE UNIT

Robert M. Hofland, Boulder, and Jack W. Stringer, Hygiene, Colo., assignors to International Business Machines Corporation, Armonk, N.Y., a corporation of New York

Filed July 15, 1968, Ser. No. 12,781

Term of patent 14 years

Int. Cl. D14—02

U.S. Cl. D26—5

FIG. 1

FIG. 2

FIG. 1 is a front and right-side perspective view of a tape unit, showing our new design.

FIG. 2 is a rear, top, and left-side perspective view of the design of FIG. 1.

The hub on the right side behind the window is adapted to receive a tape reel, cartridge, or the like.

We claim:

The ornamental design of a tape unit, substantially as shown and described.
